RACE HANDICAPPING DEVICE

William Wahrt, New York, N. Y.

Application February 16, 1945, Serial No. 578,340

5 Claims. (Cl. 235—79.5)

1

This invention relates to new and useful improvements in a race handicapping device.

More particularly, the invention proposes a handicapping device which may be used for handicapping any type of race, such as horse races, dog races, etc. However, the particular handicapping device disclosed in this specification is intended to be used for horse racing. Similar devices may be arranged to be used for any other type of races as already stated.

The horse racing handicapping device, in accordance with this invention is characterized by a shaft turnably mounted through a frame and supporting what will hereinafter be called, a first group of rollers. It is proposed that a tubular shaft will be turnably mounted on said shaft for supporting a second group of rollers. A means is provided for connecting these shafts together for unitary rotation and disconnecting them for individual rotations. It is proposed to provide a sighting bar mounted across the frame and indicating across the rollers.

It is proposed that the data on the rollers comprise certain information needed for figuring handicaps. It is contemplated that the first group of rollers include a rating roller, having peripheral divisions extending upwards and downwards from 100, representing the starting point. The first group of rollers also includes a set of reference time and distance rollers, adjustably connected with each other and with said rating roller for setting to par from the track records for the distance and time. With this arrangement it is possible to set the rating rollers in relation to the reference time, and distance rollers to represent the par of any particular track. Each racing track has a detailed record, which is available, giving their particular par. With this information it is possible to set the first group of rollers.

It is proposed that the second group of rollers include a racing data roller and a set of rollers representing lengths beaten, weight, class, and winning percentage that is in 1st, 2nd or 3rd of total starts, etc. It is proposed that this second group of rollers be so arranged that the racing data roller is adjustable relative thereto and the rolls of the group may be adjustably set in relation to each other. In this latter event all the rollers of the second group of rollers, except the racing date roller should be fixedly connected together in a group so that the racing date roller may be adjusted each day, so that the handicapping device may be used each day to figure handicaps.

2

The invention also proposes a plate with markings mounted on the frame and extending across said rollers for identifying the various rollers.

Still further the invention proposes a handicapping device as mentioned, which is simple, and which may be used with little trouble, and which may be manufactured and sold at a reasonable cost.

For further comprehension of the invention, 10 and of the objects and advantages thereof, reference will be had to the following description and accompanying drawings, and to the appended claims in which the various novel features of the invention are more particularly set forth.

15 In the accompanying drawing forming a material part of this disclosure:

Fig. 1 is a front elevational view of a race handicapping device, constructed in accordance with this invention.

20 Fig. 2 is a developed view of the entire group of rollers shown in Fig. 1.

Fig. 3 is a transverse vertical sectional view taken on the line 3—3 of Fig. 1.

Fig. 4 is a vertical sectional view taken on the 25 line 4—4 of Fig. 1.

Fig. 5 is a longitudinal sectional view of Fig. 1.

Fig. 6 is a perspective view of the device.

The race handicapping device, in accordance with this invention, includes a frame 10. This frame 10 is formed from a pair of end plates 11 which are fixedly held in spaced positions by a group of tie rods 12. A shaft 14 is turnably mounted through said frame 10 and is for the purpose of supporting a first group of rollers embraced by the bracket 16. A tubular shaft 17 is turnably mounted on the shaft 14 and is for the purpose of supporting a second group of rollers embraced by the bracket 18. The tubular shaft 17 projects from one of the end plates 11. This projecting end is provided with a knob 19 by which the shaft 17 may be pushed to engage the first group of rolls. The ends of the shaft 14 may be provided with knobs 20 by which the shaft 14 may be turned. The shaft 14 is turnably supported at one end by the tubular shaft 17. At the other end of the frame 10, the shaft 14 passes through the end plate 11 which is provided with friction washers 23. These washers are locked with nuts 21 against the end plate 11 to prevent shaft 14 and the first group of rollers from turning when the tubular shaft 17 is lined up with the said group of rollers.

The shaft 14 and the tubular shaft 17 may be connected together for unitary rotation, or they 55 may be disconnected for individual rotation, when

this is desired. The connecting means comprises a pair of opposed toothed clutch members 25, one of which is fixedly mounted on the shaft 14, the other of which is fixedly mounted on the tubular shaft 17.

The clutch members 25 are located between the groups of rollers 16 and 18. The tubular shaft 17 is capable of being manually pushed in or pulled out for engaging and disengaging the clutch members 25 from each other respectively. When the clutch members 25 are pressed against each other their teeth will interengage and then the shafts 14 and 17 are connected for unitary rotation. When the tubular shaft 17 is pulled out, the clutch members 25 will be separated and then the shafts 14 and 17 may be individually or relatively turned. The clutch members 25 are illustrated in their separated positions. The knob 19 may be pressed inwardly to engage the clutch members 25, and then the knob 19 may be used to turn the shafts 17 and 14.

The sighting bar 28 is mounted across the frame 10 and across the groups of rollers 16 and 18. This sighting bar 28 is supported upon one of the tie rods 12. Said rollers may be set in relation to this sighting bar 28 during the operation of the handicapping device. In order to avoid confusion which might be occasioned by the similarity of numbers on the rollers, a sliding guide 28' is provided on the sighting bar 28 which enables the user to follow the markings on a specific roller. A plate 29 with markings for identifying the various rollers is also mounted upon the frame 10 across said rollers. This plate 29 is pivotally supported on one of said tie rods 12. The plate 29 may be directed upwards or it may be folded down. It is pivotally supported by a pair of spaced tubular portions 30 formed along the bottom edge of the plate 29.

A support rod 33 is pivotally and non-slidably mounted upon the wire 22, and is formed with a bottom hook portion which is capable of engaging upon another one of the tie rods 12 by which the plate 29 may be held in an upwardly extending position. When the support rod 33 is disconnected from the tie rod 12, the plate 29 may be folded down. The markings upon the plate 29 will be discussed after a more detailed description of the rollers of the device.

The first group of rollers 16 includes a rating roller which is the particular design of the handicapping device is formed from two adjacent roller sections 35 and 36. The roller sections 35 and 36 are separate roller members fixedly clamped together. The roller section 35 has a starting point represented by the numeral 100. From this point the roller section 35 is graduated into readings above and below 100. At one point the scale crosses over to the roller section 36. This point is at the area between the numerals 86 and 81. The purpose of having the roller sections 35 and 36 is merely to extend the numerals. The numeral 100 on the roller section 35 is accepted as a par of the track.

The plate 25 is inscribed with the word "Rating" indicated by the reference numeral 37 at an area above the roller sections 35 and 36, indicating that these roller sections represent the rating of the handicapping device. The remaining rollers on the group of rollers 16 indicated by the reference numerals 40 to 47 inclusive, is imprinted with scales to give the time for different distances. For example the roller 49 represents 5½ furlongs, 41 represents ¾ of a mile roller 44, a mile, etc. The plate 29 is imprinted at an area

48 with the distances for the various times on the rollers 40 to 47 inclusive. Any additional distances with reference time on rollers may be used.

This area 48 of the plate 29 is also imprinted with the par time of a particular track for these distances. This section of the plate 29 is referred to as the Reference Time and Distance portion of the plate 29. In Fig. 2 the numerals 1, 2, 3 and 4 represent fifths of a second.

Froms Figs. 1 and 2 it can be observed that the par rating 100 of the track on the rating roller section 35 is set to the par time on the group of rollers 40 to 47 inclusive. The par position is made clear by a heavy imprinted line 49, or a colored line. All of the rollers of the first group of rollers 16 are clamped together as a unit. This clamping is accomplished by a nut 50 which is threadedly mounted upon the shaft 14 and which engages against the outer face of the roller 35, forcing all of the rollers of the group 16 against the clutch 25 which is mounted on the shaft 14. The nut 50 is formed with several peripheral openings 51 into which a turning tool may be engaged by which the nut 50 may be loosened. Thus, the various rollers of the group 16 may be reset into selected positions. In this way the handicapping device may be reset to represent the par of any track.

The second group of rollers 18 includes a racing date roller 53. This racing date roller 53 is imprinted with numerals from 1 to 30 and represents the days of the month. The 31st day may be represented by the 1. This numeral 1 is also used to represent the first day of the month. The racing date roller 53 is loose on the tubular shaft 17. However, a friction washer 54 is coaxially mounted on the tubular shaft 17 and is interposed between the racing date roller 53 and the adjacent roller of the group of rollers 13, and is for the purpose of frictionally holding the racing date roller 53 stationary in relation to the remaining rollers of the group.

The date roller is divided into 30 equal spaces, the same spacing of the time rollers covers six seconds or thirty-fifths in the first group of rollers. One-fifth of a second in time equals one beaten length so that the approximate running time for a beaten horse for a certain distance and track may be established by adding beaten lengths to the winner's time. The time figures on the rollers may be extended above and below a par reference time if necessary as shown in Fig. 2. It is to be understood that any suitable spacing may be used for the time rollers.

The remaining rollers consist of a Length Beaten roller 56, a Weight roller 57, a Class roller 58, and a Percentage Winning roller 59. These rollers are all identified by printed markings, as shown in Fig. 1, on the plate 29 at positions above said rollers. A par line 49' is drawn across the rollers 56 and 59 inclusive.

On one of the end plates 11 an opening 60 is provided. Corresponding openings 61 are formed in roller sections 35 to 47 inclusive, so that these roller sections may be aligned to the desired set of reference time for the different distances by inserting a pin or rod through the opening 60 and corresponding openings 61 in the rollers. Nut 50 is then tightened and the bar is withdrawn.

The operation of the race handicapping device may be understood from the following:

Assume that it is desired to handicap the race known as the 4th Race at Belmont which will take place on August 12. A standard racing paper

is purchased which will give the necessary information concerning the race, by which the handicapping may be done. From the newspaper it will be found that the horses racing are Pavot, Great Power, Jeep and Plebiscite. Let us assume that the handicapping device has been set for the particular track on which the race will take place.

Our first problem is to obtain the handicapping rating for the first horse Pavot. From the racing paper we note that the last prior race of Pavot took place on Aug. 5, that the race was $\frac{3}{4}$ of a mile, and that the time was 1:12 $\frac{1}{2}$. We now turn one of the knobs 20 so that we set the roller 41 which represents a $\frac{3}{4}$ mile race, so that the position 1:12 $\frac{1}{2}$ is positioned above the sighting bar 28; rating reading is now 89. We next adjust the racing date roller 53 so that the date 12 is aligned with the par line 49' of the rollers 58 to 59 inclusive. This par line 49' represents the starting point for adding or subtracting points for different factors as days, lengths beaten or stretch gain, class, percentage, etc.

Any number of rollers may be used within a frame with any desired handicapping factors marked in points on said rollers.

Since Pavot won its prior race there is no necessity of moving the lengths beaten roller 56. The rating therefore remains at 89. The next thing we do is to press the knob 19 inwards so as to engage the clutch 25 and then we turn the knob 19 so as to turn the racing date roller 53 from 12 to the date of the last race which was August 5, therefore, we turn the knob 19 clockwise until 5 is positioned above the sighting bar 28. When we turned knob 19 clockwise we subtract on the Rating roller 35 and we will find that 82 is now the rating reading.

We next set the weight roller 57. From the racing paper we note that Pavot's weight is 122. In the last race it was 126. We therefore pull out the knob 19 so as to disengage the clutch 25 and then we set the reading 126 of the weight roller 57 above the sighting bar 28. We then press in the knob 19 to engage the clutch 25 and now turn the knob 19 so as to move the 122 marking on the weight roller 57 above the sighting bar 28. We will find that the rating reading now above the sighting bar is 83.

We next draw the knob 19 out and turn the knob 19 until the par line 49' of the Class roller 58 is above the sighting bar 28. We now push the knob 19 inwards to connect the clutch 25, and turn the knob counterclockwise until we reach the Class of Pavot, which is A/W. This adds 5 points to the rating reading and it is now 88.

We now pull the knob 19 out again disengaging the clutch 25, and line the par line 49' with the sighting bar 28. We then press the knob 19 inwards to connect the clutch 25 and then turn the Percentage roller 59 counterclockwise to a percentage of winnings of Pavot, as given in the racing paper. We find that this adds 20 points, and makes the reading 108. This is Pavot's rating. In this same way the ratings of the various horses in the race are figured. Great Power's rating will be 97, Jeep's 92, and Plebiscite 106. This gives the handicapping ratios of the various horses.

Since Pavot won the last race, it may be best to consider the horse Jeep so that we may see the manner in which the Lengths Beaten roller 56 is operated. From the racing paper we see that Jeep was beaten in the last race by $\frac{7}{4}$ lengths. We line up the par line 49' with the

sighting bar 28. Then we press the knob 19 inwards so as to connect the clutch 25 and turn the knob 19 clockwise 7 $\frac{1}{4}$ lengths which will subtract 7 points from the rating of Jeep. If it is desired to take the stretch gains also into consideration, then points would be added to the ratings for stretch gains merely by turning the rollers counter-clockwise. In other respects the final rating is substantially the same as previously described.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. A race handicapping device, comprising a frame, a shaft turnably mounted through said frame for supporting a first group of individually and manually settable rollers, a tubular shaft turnably mounted on said shaft for supporting a second group of individually and manually settable rollers, means for connecting said shafts together for unitary rotation of said groups and disconnecting said shafts for individual rotation of said groups, a sighting bar mounted across said frame, a sliding guide on said sighting bar, said first group of rollers including a rating roller having peripheral divisions extending upwards and downwards from 100 representing a starting point and a set of reference, time and distance rollers adjustably connected with each other and with said rating roller for setting to par track records for the distance and time, said second group of rollers including a racing date roller and a set of rollers representing lengths beaten, weight, class, and percentage winnings fixedly connected with each other and adjustably connected with said racing date roller for daily adjustment of the date roller in relation to the other rollers, and a plate with markings mounted on said frame and extending across said rollers for identifying said rollers.

2. A race handicapping device, comprising a frame, a shaft turnably mounted through said frame for supporting a first group of individually and manually settable rollers, a tubular shaft turnably mounted on said shaft for supporting a second group of individually and manually settable rollers, means for connecting said shafts together for unitary rotation of said groups and disconnecting said shafts for individual rotation of said groups, a sighting bar mounted across said frame and with which values on the rollers are aligned and a guide slidable on said bar, said first group of rollers including a rating roller having peripheral divisions extending upwards and downwards from 100 representing a starting point and a set of reference, time and distance rollers adjustably connected with each other and said rating roller for setting to par track records for the distances and time, said second group of rollers including racing date roller and a set of rollers representing lengths beaten, weight, class, and percentage winnings fixedly connected with each other and adjustably connected with said racing date roller for daily adjustment of the date roller in relation to the other rollers, and a plate with markings mounted on said frame and extending across said rollers for identifying said rollers, said means for connecting said shafts

comprising clutch members adjacent each other and mounted upon said shafts and capable of engaging each other when said shafts are adjusted lengthwise with respect to each other.

3. A race handicapping device, comprising a frame, a shaft turnably mounted through said frame for supporting a first group of individually and manually settable rollers, a tubular shaft turnably mounted on said shaft for supporting a second group of individually and manually settable rollers, means for connecting said shafts together for unitary rotation of said groups and disconnecting said shafts for individual rotation of said groups, a sighting bar mounted across said frame and with which values on the rollers are aligned and a guide slidable on said bar, said first group of rollers including a rating roller having peripheral divisions extending upwards and downwards from 100 representing a starting point and a set of reference, time and distance rollers adjustably connected with each other and with said rating roller for setting to par track records for the distances and time, said second group of rollers including racing date roller and a set of rollers representing lengths beaten, weight, class, and percentage winnings fixedly connected with each other and adjustably connected with said racing date roller for manual daily adjustment of the date roller in relation to the other rollers, and a plate with markings mounted on said frame and extending across said rollers for identifying said rollers, said racing date roller being loose upon said tubular shaft, and a friction washer between said racing date roller and the adjacent roller of the rollers of said second group of rollers by which the racing date roller is frictionally held in a stationary position in relation to the other rollers of said second group of rollers.

4. A race handicapping device, comprising a frame, a shaft turnably mounted through said frame for supporting a first group of individually and manually settable rollers, a tubular shaft turnably mounted on said shaft for supporting a second group of individually and manually settable rollers, means for connecting said shafts together for unitary rotation of said groups and disconnecting said shafts for individual rotation of said groups, a sighting bar mounted across said frame and with which values on the rollers are aligned and a guide slidable on said bar, said first group of rollers including a rating roller having peripheral divisions extending upwards and downwards from 100 representing a starting point and a set of reference, time and distance rollers adjustably connected with each other and with said rating roller for setting par track records for the distance and time, said second group of rollers including racing date roller and a set of rollers representing length, beaten, weight, class, and percentage winnings fixedly connected with each other and adjustably connected with said racing date roller for daily adjustment of the date roller in relation to the other roller, and

a plate with markings mounted on said frame and extending across said rollers for identifying said rollers, said first group of rollers being locked together in a fixed unit by clamping nut, said nut being engageable against the outer face of the end roller of said first group of rollers and clamping said group of rollers together against a member mounted upon said shaft, nuts being threadedly mounted upon said shaft and friction washers on either side of the end plate frictionally holding the first group of rollers in any desired position.

5. A race handicapping device, comprising a frame, a shaft turnably mounted through said frame for supporting a first group of individually and manually settable rollers, a tubular shaft turnably mounted on said shaft for supporting a second group of individually and manually settable rollers, means for connecting said shafts together for unitary rotation of said groups and disconnecting said shaft for individual rotation of said groups, a sighting bar mounted across said frame and with which values on the rollers are aligned and a guide slidable on said bar, said first group of rollers including a rating roller having peripheral divisions extending upwards and downwards from 100 representing a starting point and a set of reference, time and distance rollers adjustably connected with each other and with said rating roller for setting to par track records for the distance and time, said second group of rollers representing lengths beaten, weight, class, and percentage winnings fixedly connected with each other and adjustably connected with said racing date roller to the other rollers, and a plate with markings mounted on said frame and extending across said rollers for identifying said rollers, said first group of rollers being locked together in a fixed unit by clamping nut, said nut being engageable against the outer face of the end roller of said first group of rollers and clamping said group of rollers together against a member mounted upon said shaft, nuts being threadedly mounted upon said shaft and friction washers on either side of the end plate frictionally holding the first group of rollers in any desired position and means for aligning the roller sections, said means including openings formed in the said roller sections, and one of the said end plates, 50 and a pin slidably engageable in said openings.
